SOUND APPARATUS

Karl Daniel, Cologne, Germany, assignor to Tefi-
Apparatebau Dr. Daniel K.-G., Cologne, Ger-
many

Application May 3, 1938, Serial No. 205,717
In Germany May 14, 1937

6 Claims. (Cl. 274—24)

This invention relates to improvements in and relating to sound apparatus and more particularly to the adjustment of the cutting depth of the cutting stylus or needle, especially in the case of band-like sound record carriers.

Hitherto the stylus employed for recording sound according to the needle sound method was relieved of load or balanced by means of a counter-weight or a spring, whereby the required cutting depth was obtained. The more carefully and more sharply the cutting needle or stylus was made, the more difficult was the adjustment and relieving of load of the sound box, as with a very sharp cutting needle a very slight pressure of a few grammes only suffices to produce an ample cutting depth.

Sound apparatus with such load-relieved-cutting boxes are, however, extraordinarily sensitive to the slightest disturbance, as the box is easily set in oscillation and as a consequence either too deep a cut is made or the cutting stylus or needle is lifted off the sound record carrier. Moreover, over a long recording period, the cutting stylus or needle gradually sinks more deeply into the sound record carrier with the result that, if thin band-like sound record carriers are being used, they are liable to be completely perforated.

One object of this invention is to avoid the above disadvantage and to provide an arrangement in which the swinging of the weight or spring loaded cutting or sound box in the direction of the sound record carrier is limited by a micrometer-like adjusting member.

A further object is to ensure an accurate adjustment of the cutting stylus or needle to a definite cutting depth and to prevent the said needle from cutting more deeply than necessary into the record carrier and consequently destroying it.

A still further object is to provide a cutting or sound box in which, during operation, there is no danger of the cutting stylus or needle coming out of the sound track owing to vibrations being set up.

A still further object is to provide an arrangement which will render recording possible even in moving vehicles.

It will be understood that the invention is particularly suitable for use in sound apparatus where the band-like sound record carrier runs over a fixed guide path, as only in this case can a complete uniformity of the cutting depth be attained. In other sound apparatus, in which the sound record carrier lies, in the cutting position, on a rotating path, this is indeed theoreti-

cally, but not practically possible, as rotating bodies cannot be made to run so uniformly that small oscillations, produced by bearing-play or the like, with consequent continual variation of the depth of cut do not occur.

In order that the invention may be fully understood, I shall now describe one embodiment thereof, by way of example, by reference to the accompanying diagrammatic drawing, in which:

10 Fig. 1 shows the invention in side view, and
Fig. 2 is a vertical section on the line II—II of Fig. 1.
15 The cutting or sound box *a* is rotatably and, if necessary, axially displaceably carried on a spindle *b* carried on the sound apparatus. The band-like sound record carrier is guided over a fixed guide path *d* under the cutting stylus or needle *c*. On an arm *e* carrying the cutting box is arranged a rod *f* which projects with its free 20 end beyond the spindle *b* so that the said spindle *b* forms a pivot point for the double-armed lever *e*, *f*. On the free end of the said rod *f* is rotatably arranged an eccentric *g* which is adjustable through the medium of a knob *h*. The eccentric 25 *g* bears with its upper edge against a transverse bar *i* which is secured at one end thereof to the sound apparatus between two shoes *k*. A micrometer screw device *l* carried by a mounting bracket *l'* secured to the frame of the sound apparatus acts on the free end of the said transverse rod *i*. By means of the rod *f* of the sound box or the eccentric *g* arranged on said rod an upward pressure is exerted on the transverse bar *i*. The latter is, however, prevented from moving upwardly by the micrometer screw device *l*. If the eccentric *g* is rotated by the knob *h*, the transverse bar *i* will not alter its position but the rod *f* and with it the sound box will be raised or lowered. If, on the other hand, the micrometer 30 screw device *l* is actuated, then the bar *i* is at least in part displaced upwardly or downwardly together with the eccentric *g* arranged on said rod and the rod *f* and sound box *a*.

The method of operation of the arrangement 35 is as follows: First the cutting stylus or needle *c* is brought into contact with the sound record carrier by rotation of the eccentric *g* which serves for the coarse adjustment, and which can, if desired, be replaced by any other suitable device.

40 Then the fine adjustment is effected by means of the micrometer screw device *l*, which adjustment can be measured by a scale. The gauge of the micrometer screw device can, in a simple manner, be arranged on the disc-like rotary head 45 *m* thereof.

I claim:

1. An arrangement for adjusting the cutting depth of the cutting stylus in sound apparatus including a sound record carrier comprising the sub-combination of: a support; a double-armed lever member pivoted to said support; a sound box carrying a cutting stylus and carried by one arm of said lever member; a bar adjacent the free end of the other arm of said member, said bar being movably secured at one end to said support; a rotatable eccentric carried by said free arm end, said eccentric engaging said bar and serving for coarsely adjusting said sound box; and a micrometer-like adjusting device carried by said support, said device engaging the free end of said bar and serving for the fine adjustment of the said sound box relative to the sound record carrier.

2. An arrangement for adjusting the cutting depth of the cutting stylus in sound apparatus including a sound record carrier comprising the sub-combination of: a support, a double-armed lever member pivoted to said support; a sound box having a cutting stylus and carried by one arm of said lever member; means including a part carried by the other arm of said lever member and a second part movably connected to the support for effecting a coarse adjustment of said cutting stylus relative to the sound record carrier; and movable means carried by said support and engaged with said second part and operative for effecting a fine adjustment of said stylus.

3. An arrangement for adjusting the cutting depth of the cutting stylus in sound apparatus including a sound record carrier, comprising the sub-combination of: a support; a double-armed lever member pivoted to said support; a sound box having a cutting stylus carried by one arm of said lever member; a coarse adjustment device for said stylus including a part carried by the other arm of said double-armed lever member and a second part movably connected to the support; and a micrometer device carried by said support and engaged with said second part and operative for effecting a fine adjustment of said stylus relative to said sound record carrier.

4. An arrangement for limiting the cutting

depth of the cutting stylus in sound apparatus including a sound record carrier, comprising the sub-combination of a support, a sound box having a cutting stylus, means pivotally mounted on the support and holding the sound box for movement toward and from the sound record, and means for limiting the movement of the sound box toward the sound record including coarse adjusting means for quickly determining an approximate allowable limit of such movement and including separable parts of which one is mounted on the said pivotally-mounted means and a second part is movably affixed to the support, and fine adjusting means on the support and engageable with one of said parts for moving the same to accurately determine the exact point of limitation upon such movement.

5. A sound recording machine including a support having means for guiding a travelling sound carrier, a sound box mounted on the support for movement toward and from the sound carrier, a stylus on the sound box, and means comprising coarse and fine adjusting devices for limiting the movement of the sound box toward the sound carrier, said means including a stop member movably secured to the support, one of said devices including an adjustable part mounted to move bodily with the sound box for engaging said stop member and the other of said devices including a part carried by the support and engageable with and effective for moving the stop member.

6. A sound recording machine including a support having means for guiding a travelling sound carrier, a lever pivoted on the support, a sound box fixed on the lever and moving therewith toward and from the sound carrier, a stylus on the sound box, a stop arm movably mounted on the support, coarse adjustment means carried by the lever and engaged with the stop arm for limiting the movement of the sound box toward the sound carrier, and fine adjustment means carried by the support and engageable with and operative for determining the position of the stop arm and thereby limiting the movement of the sound box toward the sound carrier.

KARL DANIEL.
